UNITED STATES PATENT OFFICE.

FRANK C. BARKER, OF ST. PAUL, MINNESOTA, ASSIGNOR TO THE YALE & TOWNE MANUFACTURING COMPANY, OF STAMFORD, CONNECTICUT.

PIN-TUMBLER LOCK.

1,417,132.

Specification of Letters Patent. Patented May 23, 1922.

Application filed April 9, 1921. Serial No. 459,362.

To all whom it may concern:

Be it known that I, FRANK C. BARKER, a citizen of the United States, and a resident of St. Paul, in the county of Ramsey and State of Minnesota, have invented certain new and useful Improvements in Pin-Tumbler Locks; and I do hereby declare the following to be a full, clear, and exact description of the invention, such as will enable others skilled in the art to which it appertains to make and use the same.

This invention relates to an improvement in pin tumbler locks.

It is a known fact that it is possible to unlock the plug of a pin tumbler lock without a key, by means of slim picking tools operated through the key hole to raise the pins to the proper height. To do this however it is necessary to apply a side pressure upon the pins after they have been raised to prevent them from dropping under the pressure of the springs, which is accomplished by a small wrench or similar tool inserted in the key hole and upon which a slight pressure is exerted tending to revolve the plug and thus clamp the pins in their elevated position.

The object of my invention is to provide a mechanism which will prevent the application of any side pressure on the pins, and it consists in the parts and combinations of parts as will be more fully explained and pointed out in the claims.

In the accompanying drawings, Figure 1 is a view in front elevation of the pin tumbler lock; Figure 2 is a view in section on the line 2—2 of Figure 1; Figure 3 is a view in transverse section on the line 3—3 of Figure 2; Figure 4 is a view in rear elevation of the lock with the disk removed; Figure 5 is a view in elevation of the cam; Figure 6 is an edge view of the latter; Figures 7 and 8 are views in front and edge elevation respectively of the disk; Figure 9 is a view showing the relation of the disk to the cam, and Figures 10 and 11 are views of a modified construction.

10 represents the cylinder and 11 the key plug, which are of the usual construction except that in the locks as now made, the plug 11 has a close fit within the bore of the cylinder and is connected directly with the cam.

In my improvement, the cylinder is coun-

terbored at the rear of the opening for the 55 key plug to receive the cylindrical sleeve 12 which has a close fit in said counterbore and is prevented from outward displacement by the shoulder formed by counterboring and is provided with a bore to receive the key 60 plug 11.

The outer end of the plug 11 is flanged as at 13, the said flange resting within a circular recessed seat formed in the front or outer face of the cylinder 10 so as to prevent any rearward movement of the plug within the sleeve. The cylinder 10, sleeve 12 and plug 11 are provided with pin holes, in which are located the sectional pins 14 which, in Figures 2 and 3, are each composed 70 of cylindrical pin sections and the ball or balls 15, the latter being interposed between sections of the pins and constituting parts of the latter, and which in Figures 10 and 11 are composed wholly of cylindrical sections the lower section 14^a, which normally rests in the plug, having convex ends which engage the sections next above.

In the ordinary cylinder lock, when the proper key is inserted, the pins are so moved 80 that a break or joint in each sectional pin occurs at the surface of the plug and thus allow the plug to be revolved by the key and actuate the cam. In my improvement the cam 16 instead of being secured to the plug 85 is secured by screws 17 to the sleeve 12, so that it is necessary to rotate the sleeve in order to turn the cam which actuates the associated lock mechanism, and when the proper key is inserted a break or joint in 90 each pin occurs always at the surface of the sleeve, and as the plug and sleeve are thus locked together by the pins, the plug and sleeve will be turned together.

The novel feature of my invention resides 95 in the plug which is provided with one or more pins each composed of a pin section or sections and a ball or balls in each pin hole as shown in Figure 2, or a pin section with a convex end bearing against the section next above, as shown in Figures 10 and 11, and so located that a ball or the convex end of a pin section 14^a, as the case may be, in each pin hole rests flush with the surface of the plug when the key is not 105 inserted, thus leaving the plug floating or free to be revolved under any turning pressure exerted upon it, and as the sleeve is

wholly concealed at the front so that no access can be had to it, it is impossible to obtain any side pressure upon the sections of the pins above the plug, sufficient to hold 5 the latter elevated against the pressure of the springs 18. In Figures 2 and 3 the pin hole in each plug 11 is shown provided with a short section of a pin and two balls, but it is clearly evident that I may use only 10 one ball or more than two, or, as above stated I may dispense with the balls and use pin sections with convex ends as shown in Figures 10 and 11.

The cam 16 which actuates the associated 15 lock mechanism, is secured to the sleeve 12 by the screws 17, and the inner end of the plug which passes through the cam is covered by a disk 19 secured to the inner end of the plug, the outer edge or periphery 20 of the disk overlapping the cam, thus locking the plug against outward displacement. The face of the disk 19 contacting with the cam 16 may be perfectly flat to permit of 25 unlimited rotation of the plug and disk in either direction when the key is not inserted

in the plug, but, I prefer to provide the cam with one or more shoulders 20, and the disk with corresponding recesses 21 of greater length than the width of the shoulders to 30 permit of a limited movement only of the plug within the sleeve. When the parts are thus assembled the plug 11, sleeve 12 and cam 16 are secured to the cylinder 10 between the plug head or flange 13 and the 35 disk 19, and as before explained the plug may be free when the key is not inserted, to make a complete revolution within the sleeve, but I prefer to limit the movement by the shoulder 20 and recess 21 connection between the disk and cam as previously explained.

With this construction, the balls or the pin sections having convex ends normally rest within the plug flush with the outer 45 surface thereof, thus leaving the plug floating or free to be turned. When a key or picking tool is however inserted in the key slot, a ball or balls or curved end of the pin sections in the plug are raised to project into the sleeve thus locking the plug to the sleeve, and if the proper key be used the joints in the sectional pins 14, will be brought into alinement with the outer surface of the sleeve thus permitting the latter and the cam 16 secured thereto, to be turned to actuate the associated lock mechanism. If however picking tools be used, there can be no side pressure exerted through the balls or the convex ends of the 50 pin sections 14^a to the pin sections above, consequently there can be no clamping action exerted on the upper sections of the pins that would be sufficient to prevent them from being acted upon by the springs 18, 55 hence it is impossible to hold the pins ele-

vated by a side pressure. This renders the process of picking the lock more difficult and consequently adds security to the lock.

In order to yieldingly hold the key plug 11 in proper position for the entrance of 70 the key, I have provided the plug with a spring pressed ball 22 adapted to engage a recessed seat in the sleeve. The ball will give or yield and permit the plug to turn when a key or other instrument is inserted 75 in the key slot of the plug and turned in either direction and which will seat itself when the plug has been returned to its normal position.

It is evident that many slight changes 80 might be resorted to in the relative arrangement of parts shown and described without departing from the spirit and scope of my invention hence I would have it understood that I do not wish to confine myself 85 to the exact construction and arrangement of parts shown and described but,

Having fully described my invention what I claim as new and desire to secure by Letters Patent, is:—

90

1. In a pin tumbler lock, the combination of a cylinder, a sleeve mounted to rotate therein, a key plug mounted to rotate in the sleeve, a cam secured to the sleeve for actuating the associated lock mechanism, 95 and a pin to normally lock said sleeve to said cylinder composed of a pin section and a member below said section, the said lower member having a convex surface engaging the pin section above the same and normally 100 resting in the plug and adapted to elevate the pin section, whereby the sleeve will be disconnected from the cylinder.

2. In a pin tumbler lock, the combination of a cylinder, a sleeve mounted to rotate 105 therein, a plug mounted to rotate in the sleeve, a cam secured to the sleeve for actuating the associated lock mechanism, and a pin composed of pin sections and a lower member located within the plug and having 110 a convex surface engaging the section next above, the said lower member of the pin normally resting within the plug with its upper surface flush with the surface of the plug whereby the latter is normally free to rotate 115 in the sleeve, and a pin section above the said lower member normally locking the sleeve to the cylinder.

3. In a pin tumbler lock, the combination of a cylinder, a sleeve mounted to rotate 120 therein, a key plug mounted to rotate in the sleeve, a cam secured to the sleeve for actuating the associated lock mechanism, and a pin for locking the sleeve against rotation, the said pin being composed of sections one 125 of which normally rests in the plug with its surface flush with the outer surface of the plug whereby the latter is normally free to rotate in the sleeve, the upper surface of the pin section in the plug being convex. 130

4. In a pin tumbler lock, the combination of a cylinder, a sleeve mounted to rotate therein the front end of the sleeve bearing against the front face of the cylinder, a plug mounted to rotate in the sleeve the outer end of the plug overlapping the front part of the cylinder so as to prevent rear end displacement of the plug, a cam secured to the sleeve, means for preventing outward displacement of the plug and a pin for locking the sleeve against rotation in the cylinder, the said pin being composed of pin sections and a ball, the latter normally resting within the plug and adapted when elevated by the key to elevate the pin sections so that the joint in the latter will be flush with the outer surface of the sleeve thus leaving the latter free to be turned with the plug.
5. In a pin tumbler lock, the combination of a cylinder, a sleeve mounted to rotate therein, a plug mounted to rotate in the sleeve, the cylinder, sleeve and plug being provided with a pin hole, a pin made up of sections and a ball the latter normally resting within the plug with its outer surface flush with the outer surface of the latter and a pin section normally engaging the sleeve and the cylinder for holding the former against rotation, a cam secured to the sleeve and means for securing the plug against endwise displacement.
6. In a pin tumbler lock, the combination of a cylinder, a sleeve mounted to rotate therein, a plug mounted to rotate in the sleeve, a cam secured to the sleeve, a disk secured to the plug and overlapping the cam, the cylinder, sleeve and plug being provided with pin holes, and a pin mounted in each hole each pin being composed of pin sections and a ball the latter normally resting within the plug with its outer surface flush with the outer surface of the latter so as to permit of rotation of the plug within the sleeve, and the pin sections normally resting in the holes in the sleeve and cylinder for preventing the latter from being turned.
7. In a pin tumbler lock, the combination of a cylinder, a sleeve mounted to rotate therein, a plug mounted to rotate in the sleeve, the cylinder, sleeve and plug having aligned pin holes, a pin in each pin hole, each pin being composed of pin sections and balls, the latter being interposed between two sections of each pin, a cam secured to the inner end of the sleeve and overhanging the cylinder, and a disk secured to the inner end of the plug and overhanging the cam.
8. In a pin tumbler lock, the combination of a cylinder, a sleeve mounted to rotate therein, a plug mounted to rotate in the sleeve, the cylinder, sleeve and plug having aligned pin holes, means for yieldingly holding the plug against rotation, a pin in each pin hole, each pin being composed of pin sections and balls the latter being interposed between two sections of each pin and normally resting in the plug, a cam secured to the inner end of the sleeve and overhanging the cylinder and a disk secured to the inner end of the plug and overhanging the cam.
9. In a pin tumbler lock, the combination of a cylinder, a sleeve mounted to rotate therein, a plug mounted to rotate in the sleeve, a cam secured to the inner end of the sleeve, a disk secured to the inner end of the plug, the cam and disk having engaging parts for limiting the independent rotation of the plug in the sleeve, the cylinder, sleeve and plug having aligned pin holes and a pin in each hole, each pin composed of pin sections and balls interposed between the pin sections, the balls normally resting within the plug, substantially as and for the purpose described.

In testimony whereof, I have signed this specification in the presence of two subscribing witnesses.
